ROTARY OIL WELL DRILL BIT

Clifford R. Foster, Avoca, Tex.

Application January 25, 1938, Serial No. 186,884

5 Claims. (Cl. 255—76)

This invention relates to a rotary oil well drill bit and has for the primary object the provision of a device of this character which when brought in engagement with a formation under the weight of its operating medium will assume a cutting position and will collapse when lifted from said formation so that a well drilled by the device will have a diameter greater than the collapsed diameter of the drill bit whereby the latter may be freely withdrawn from the well and will permit the use of a well casing of one diameter throughout the depth of the well, thereby materially reducing the cost of a well casing by eliminating the necessity of having to employ different size well casings throughout the depth of the well.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating a rotary drill bit constructed in accordance with my invention and showing the same in an inoperative or collapsed position.

Figure 2 is a vertical sectional view illustrating the same.

Figure 3 is a vertical sectional view showing the bit extended or in an operative position.

Figure 4 is a sectional view taken on the line 4—4 of Figure 1.

Figure 5 is a sectional view taken on the line 35 5—5 of Figure 1.

Figure 6 is a perspective view illustrating a body of the drill bit.

Figure 7 is a perspective view illustrating one of the cutting elements.

Referring in detail to the drawings, the numeral 1 indicates a body having wrench engaging faces 2 and one end reduced and screw threaded to form an attaching shank 3 for detachably securing the body on a drill stem or rod. Formed in opposite faces of the body 1 are elongated grooves 4 which also open outwardly through one end of the body. The grooves 4 being formed in the body define therein a separating partition 5 for said grooves. The body 1 is cut away to expose one end of the partition which is in the form of a head 6 having a socket 7 communicating with a guide bore 8 formed in the partition. The head 6 is disposed below the lower ends of the grooves 4.

Cutting elements 9 are pivotally mounted in

the upper ends of the grooves above the upper end of the partition 5 and each includes a shank 10, a pivotal end 11 and a cutting end 12. The pivotal ends 11 of the cutting elements are arranged in overlapped relation within the upper ends of the grooves, the latter having communication with each other at their upper ends. The shanks 10 lie in the grooves 4 at opposite sides of the partition 5. The width of the pivotal and cutting ends of the cutting elements is greater than the width of the shanks. The cutting ends 12 are beveled to present cutting edges 13 extending the full width of the cutting ends. The shanks 10 have formed thereon beveled stop shoulders 14 to abut beveled portions 15 of the body 1 when the cutting elements are in inoperative or non-cutting position. A feeder 16 of a conventional construction includes a head 17 slideable in the socket 7 and carries a guide pin 18 operable in the guide bore 8. Arms 19 are pivoted on the head 17 and on the cutting elements for the purpose of bringing about spreading of the cutting elements by a downward movement of the body relative to the feeder due to the feeder contacting a formation and the body being under the weight of a drill stem or the like. The cutting elements when spread by the feeder move outwardly of the grooves 4 so as to cut a hole in a formation of a diameter greater than the diameter of the body.

A skirt 20 is mounted on the body and includes offset diverging portions 21 overlying portions of the grooves 4 to limit the spreading of the cutting elements. The skirt 20 is secured on the body by set bolts 22. The diverging portions 21 of the skirt terminate above the cutting ends of the cutting elements and are arranged inwardly of the outer cutting corners of said cutting elements so that the latter when cutting a hole in the formation will form the hole of a diameter that the skirt in entirety may move freely through. When the drill stem (not shown) is lifted, lifting the body 1 consequently removing weight therefrom the feeder 16 moves downwardly and the cutting elements move inwardly into the grooves 4 and inwardly of the diverging portions of the skirt, permitting the drill bit to move freely upwardly of the well without the danger of wedging against walls of the well. By forming the well of a diameter greater than the diverging portions of the skirt will permit the sinking into the well a well casing of a diameter the same throughout the depth of the well.

Flexible bumpers 23 are secured on the cutting elements for the purpose of contacting the lower

end of the well casing during the outward movement of the bit when being withdrawn from the well so as to assure collapsing or inward movements of the cutting elements.

5. The upper portion of the skirt 20 is provided with openings 24 to expose the wrench faces 2 of the body so that a wrench may be readily adapted thereon.

The upper portion of the body has a fluid bore 10 25 which opens outwardly through the shank to receive the usual cleaning fluid under pressure employed in a well. Branch passages 26 connect with the passage 25 and open outwardly in the grooves adjacent their lower ends for the purpose 15 of directing the fluid against the cutters to remove cuttings therefrom.

One of the passages 26 has an auxiliary passage 20 27 opening outwardly at the upper end of the partition 5 so that fluid may enter the grooves adjacent their upper ends to expel cuttings and foreign matter therefrom, consequently permitting the cutting elements to move freely within their grooves.

What is claimed is:

25. 1. A rotary drill bit comprising a body having opposed grooves connecting with each other adjacent the upper end of the body, cutting elements each including a shank, a pivotal portion and a cutting end with the pivotal portion in the connecting portions of the grooves disposing the shanks in the grooves and the cutting elements at the lower ends of the grooves and partially outwardly thereof, a pivot carried by the body and connecting the pivotal portions of the cutting 30 35 elements in overlapping relation, means carried by said body for limiting the movement of the cutting elements out of the grooves, said grooves defining therebetween a partition provided with a recess and a guide bore, a feeder including a head slideable in said recess and a guide plunger integral therewith and slideable in the bore, connecting links pivoted on the head and the cutting elements to bring about spreading of the cutting elements on engagement of the feeder with a 40 45 formation.

45. 2. A rotary drill comprising a body having grooves communicating with each other adjacent one end of the body and separable from each other adjacent the other end of the body by a partition forming a portion of the body, cutting elements pivotally mounted in the communicating ends of the grooves and having cutting ends movable out of said grooves, a feeder slidably supported by the partition, links connecting the feeder to the cutting elements to spread the latter to position the cutting ends outwardly of the grooves 50 55 on the engagement of the feeder with a formation, the engagement of the feeder with a formation, means carried by the body and including portions overlying the grooves and diverging from the body to limit the outward movement of the cutting elements with respect to said grooves, resilient bumpers carried by the cutting elements and projecting outwardly beyond the diverging portions of said means to engage with an obstruction for collapsing of the cutting elements into the grooves on the lifting of the body. 35

5. A rotary drill comprising a body having grooves communicating with each other adjacent one end of the body and separable from each other adjacent the other end of the body by a partition forming a portion of the body, cutting elements pivotally mounted in the communicating ends of the grooves and having cutting ends movable out of said grooves, a feeder slidably supported by the partition, links connecting the feeder to the cutting elements to spread the latter to position the cutting ends outwardly of the grooves on the engagement of the feeder with a formation, means carried by the body and including portions overlying the grooves and diverging from the body to limit the outward movement of the cutting elements with respect to said grooves, resilient bumpers carried by the cutting elements and projecting outwardly beyond the diverging portions of said means to engage with an obstruction for collapsing of the cutting elements into the grooves on the lifting of the body, said body having fluid passages opening outwardly in the grooves for directing fluid therein and against the cutting elements to remove foreign matter. 40 45 50 55

one end of the body and separable from each other adjacent the other end of the body by a partition forming a portion of the body, cutting elements pivotally mounted in the communicating ends of the grooves and having cutting ends movable out of said grooves, a feeder slidably supported by the partition, links connecting the feeder to the cutting elements to spread the latter to position the cutting ends outwardly of the grooves on the engagement of the feeder with a formation, and means carried by the body and including portions overlying the grooves and diverging from the body to limit the outward movement of the cutting elements with respect to said grooves. 5

4. A rotary drill comprising a body having grooves communicating with each other adjacent one end of the body and separable from each other adjacent the other end of the body by a partition forming a portion of the body, cutting elements pivotally mounted in the communicating ends of the grooves and having cutting ends movable out of said grooves, a feeder slidably supported by the partition, links connecting the feeder to the cutting elements to spread the latter to position the cutting ends outwardly of the grooves on the engagement of the feeder with a formation, means carried by the body and including portions overlying the grooves and diverging from the body to limit the outward movement of the cutting elements with respect to said grooves, and resilient bumpers carried by the cutting elements and projecting outwardly beyond the diverging portions of said means to engage with an obstruction for collapsing of the cutting elements into the grooves on the lifting of the body. 30 35

5. A rotary drill comprising a body having grooves communicating with each other adjacent one end of the body and separable from each other adjacent the other end of the body by a partition forming a portion of the body, cutting elements pivotally mounted in the communicating ends of the grooves and having cutting ends movable out of said grooves, a feeder slidably supported by the partition, links connecting the feeder to the cutting elements to spread the latter to position the cutting ends outwardly of the grooves on the engagement of the feeder with a formation, means carried by the body and including portions overlying the grooves and diverging from the body to limit the outward movement of the cutting elements with respect to said grooves, resilient bumpers carried by the cutting elements and projecting outwardly beyond the diverging portions of said means to engage with an obstruction for collapsing of the cutting elements into the grooves on the lifting of the body, said body having fluid passages opening outwardly in the grooves for directing fluid therein and against the cutting elements to remove foreign matter. 40 45 50 55
